EXTENSION LEAF TABLE

Charles H. Schnorr, Springdale, Pa.

Application January 29, 1947, Serial No. 724,942

11 Claims. (Cl. 311—55)

1

My invention relates to tables, particularly to tables having one or more leaves that are extensible to increase the effective areas of the table tops.

Tables provided with extensible leaves have been known to the art for years, but it is to be understood that my invention comprises certain new and useful improvements in table construction, whereby a table, having the attractive appearance of a solid-top table, may include one or more leaves that can be moved from a position of absolute concealment into a position of alignment with the table top. My table structure is particularly, though not exclusively, designed for metal tables, and the invention embraces improvements in the mechanism whereby a table leaf may be readily moved from position of concealment into position of service.

The invention will be understood upon reference to the accompanying drawings, in which:

Fig. 1 is a perspective view of a table embodying a construction of the invention, the view showing a table having two leaves that are in retracted and concealed position;

Fig. 2 is a view similar to Fig. 1, showing the leaves of the table extended into service position;

Fig. 3 is a larger view of the table, as seen in plan from above, with the two leaves extended;

Fig. 4 is a fragmentary sectional view on still larger scale than Fig. 3, showing certain details of construction of the table-top-operating mechanism on the vertical plane of section illustrated at IV—IV in Fig. 3;

Fig. 5 is a fragmentary view, showing the table-top-operating mechanism on the plane V—V of Fig. 3;

Fig. 6 is a view similar to Fig. 5. Whereas Fig. 5 shows the operating mechanism of the table top in normal position, Fig. 6 shows the mechanism in an intermediate position, in the course of raising the table top into the position wherein one or both of the leaves of the table top may be extended;

Fig. 7 is a fragmentary view of the structure as seen on the section plane VII—VII of Fig. 4, although it is to be noted that the main panel of the table top and one of the leaves appear in the view in elevation. In this view the table top and leaf are shown in fully raised position, ready for the leaf to be drawn from retracted position beneath the main panel of the table top;

Fig. 8 is a view similar to Fig. 7, showing the leaf drawn into extended position from beneath the raised main panel of the table top;

Fig. 9 is a view similar to Fig. 8, showing the

2

main panel lowered into common plane with the extended leaf; and

Fig. 10 is a fragmentary view comparable with Fig. 6, illustrating a modification in the structure of the table-top-operating mechanism.

The table of the invention is in this case constructed of metal, comprising a frame formed of a peripherally extending skirt 2, to which four table legs 3 are secured, as by means of screws 4 having heads 5 of the ornamental design shown on the outer face of the skirt, and provided with wing-nuts 6 engaging leg-securings angle clamps 7, as indicated in Fig. 3. The skirt 2 is formed of an extruded or rolled section of metal, typically aluminum, and is deleted on one side to receive a drawer 8, carried on slide members 9, 9 that traverse the skirt from side to side and reinforce the structure, as well as support the drawer. Other than in the drawer opening the body of the skirt 2 is of uninterrupted continuity. The body or section of the metal of which the skirt is formed includes a vertical web portion (to which the reference numeral 2 is applied) having at its lower edge an inwardly directed flange 2a. At an interval above the flange 2a an inwardly directed flange 2b is integrally formed with the web portion, and this flange 2b is also spaced at an interval below the upper edge of the vertical web portion, as shown in Figs. 4 and 7. These flanges 2a and 2b, extending peripherally of the skirt, make for sturdiness and strength of table construction, it being noted that the legs 3 may be kerfed to fit over the lower flange 2a, as shown at 2c in Fig. 9. Alternately, the flange 2a may be cut away from the web 2 at the four corners of the table, snugly to receive the table legs without the provision of kerfs.

The top of the table comprises a main panel 10 and two leaves 11 and 12. The panel and leaves are each formed of wood 13 (Fig. 4), carrying on its top and side edges a facing 15 of sheet aluminum, stainless steel, Monel metal, or plain steel coated with porcelain enamel, and between such facing and the wooden body an intervening layer 14 of felt, asbestos paper or other insulating material is interposed.

The leaves 11 and 12 of the table normally lie retracted beneath the main panel 10 of the table top, and the main panel 10 is normally nested within the upper peripheral edge of the skirt 2, as indicated in Figs. 1 and 4, this arrangement absolutely screening the leaves 11 and 12 and providing an extension table that in normal position of leaf adjustment has the attractive aspects of a solid-top table.

In accordance with my invention means are provided for raising the main top panel 10 and the leaves 11 and 12 from nested position within the upper edge of the skirt 2, to bring the leaves from concealment and into position where either or both leaves may be drawn from beneath the panel 10 and extended outward over the upper edge of the skirt 2, whereupon the panel may be shifted vertically relatively to the extended leaves and the leaves and panel arranged in common plane, as shown in Fig. 2. The invention further consists in a particularly effective mechanism for the purpose of so manipulating the table parts.

The main panel 10 of the table top is secured to the table frame by means of two telescopic supporting devices, each comprising two members 15 and 17, arranged with one member secured to the skirt 2 of the table frame and the other member secured to the nether face of the panel 10, and with the two members arranged in vertically sliding assembly one within the other, whereby the table top, otherwise rigidly secured to the table frame, may be vertically adjusted, as will presently appear. More particularly, the members 15 and 17 are formed of plate metal; the outer member 15 of the telescopic assembly is of vertical tubular form, rectangular in horizontal section, and having tangs 16 extending laterally from its body, and riveted, as at 16a, to the flanges 2a and 2b of the skirt 2 of the table frame. The member 17, slidably engaged in the bore of tubular member 15, is provided with a horizontal flange portion, by means of which it is rigidly attached, as by screws 18, to the panel 10. With the panel 10 thus secured at its opposite ends or sides to the table frame, the mechanism for vertically shifting the panel may readily function.

Such mechanism includes an arm 19 pivoted at 20 to the outer member 15 of each telescopic panel-securing device, and an arm 21 pivoted at 22 to the inner member 17 of each of said devices. The two arms are articulated by means of a pin 23, and the two arms are arranged to extend at an acute angle to one another when the panel 10 is in its lower or normal position, as shown in Figs. 1 and 5. If then, the two sets of arms 19 and 21 are manipulated simultaneously (one set of arms being provided with each of the two telescopic panel-securing devices 15, 17) to increase the angularity of the arms, the two members 17 will be forced upward in the two members 15, thereby raising the panel 10. In order to effect such movement of the two sets of arms 19 and 21 simultaneously, the means for pivotally attaching the arms 21 to the members 17 of the two panel securing devices comprise a shaft 24 that extends from one end of the table to the other, and is journaled at its two ends in the bodies of the members 17, as well as in two intermediate bearings 25 on the panel 10, which will be later described. At each end the cylindrical body of the shaft is flattened, as at 24a, and the arms 21 are snugly mounted on the so formed ends of the shaft, with the consequence that the two arms 21 and the shaft must rotate in unison. Since the two arms 19 are pivoted to the arms 21, the operation of the pair of arms 19, 21 at one end of the table is simultaneously effected in the arms 19, 21 at the opposite end of the table. In order to rotate the shaft, the arm 21 at one end of the table is continued outward from the pin 23 in a lever 26, equipped at its end with a handle 27.

The person desiring to raise or lower the table top may readily reach under the skirt 2 and grasp the handle 27. By pulling downward on the handle the lever 26 may be swung clockwise (compare Figs. 5 and 6) thereby rotating the shaft 24 and moving the arms 19 and 21 at each end of the table towards a position of vertical alignment, which in turn effects the rise of the table top above the upper edge of the skirt 2. It will be seen, therefore, that by manipulating the lever 26, the table top may be raised, and, if raised, may be lowered. In the ensuing specification where reference is made to the raising or lowering of the table top or panel 10, it will be understood that the movement is effected by such manipulation of the lever 26. Suffice it at this point to note that the telescopic supporting devices 15, 17 at the two ends of the table accurately support the table panel or top for vertical movement between nested position within the upper edge of the skirt 2 and elevated position above such edge, in the latter of which positions the leaves 11 and 12 may be adjusted. The upper edge of each supporting member 15 and the lower edge of each member 17 are notched, as indicated at 28 and 29 in Fig. 6, to provide clearance for the shaft 24 and the pin 20, respectively, when the table panel is in its lower position, nested within the upper edge of the skirt 2, with the support members 11 fully telescoped within members 15. It may also be noted that the flange portions 17a of the outer supporting members 17 are windowed, as at 17b, to provide clearance for the upper ends 30 of the arms 21 that are secured on the shaft 24.

The leaves 11 and 12 are supported upon the under face of the top panel 10, and the means for this purpose comprise a spaced pair of bars 30 and 31 for each leaf, slideably engaged by bearing members 26 that are secured by screws 32 to the bottom of the panel 10. The engagement of the bars 30 and 31 in the bearing members 26 is such that the leaves may, when the panel 10 is raised to lift the leaves above the upper edge of the skirt 2, be withdrawn horizontally from position beneath the panel 10. Additionally, the structure of the slide-bar and bearing assembly is such that vertical movement as well as horizontal movement of the leaves relatively to the panel is permitted.

Considering the preferred structure herein illustrated, it will be noted that the bars 30 and 31 are formed of plate metal, stamped or die-pressed into the form shown, each bar including an outer portion 33 to which a leaf is secured by means of screws 34. Inward from the portion 33 each slide bar 30 and 31 is formed with a broader body portion 35 that includes an elongate slot 36, through which extends a pair of pins 37, 38, carried by the associate bearing 26. More particularly, each bearing 26 consists of a metal bracket, including a basal portion 25b, two hub portions 25c, and two depending support portions 25a. The screws 32 that secure each bearing 26 to the panel 10 extend through and engage the basal portion 25b to the panel; the shaft 24 of the panel-actuating mechanism extends through and is medially supported by the hub portions 25c; and the support portions 25a carry the pins 37, 38 that secure the leaf-supporting bars 30 and 31 to the bearing. The support portions 25a of the two bearings 26 severally engage and support the bars 30 or 31

of the two leaves 11 and 12, as may be seen in Fig. 3.

The two pins 37, 37 that are carried by each support portion 25a for the support of a slide-bar 30 or 31 are preferably provided in the form of rollers or flanged wheels, as shown, thereby minimizing resistance to the sliding movement of the bars relatively to their supporting elements 25a. Furthermore, the two pins or wheels that slideably engage each bar to its support portion are spaced apart longitudinally of the slot 36 in the bar. Thus, it will be understood that, when the table top (comprising the panel 10 and the leaves 11 and 12) is raised from nested position within the upper edge of the skirt 2 of the table frame, either or both of the leaves 11 and 12 may be drawn from beneath the panel 10 outward over the upper edge of the skirt.

Fig. 7 illustrates the table top moved into raised position, and it will be perceived that not only are the panel and the leaves raised above the upper edge of the skirt 2, but the portions 33 of the leaf-supporting bars 30 and 31 are also positioned to clear the edge of the skirt. Fig. 7 illustrates the table structure fragmentarily, and shows only one of the two leaves—the leaf 11, but the description of the manipulation of this leaf will serve for both. While the table top is being raised, the leaf 11 remains snug against the bottom of the panel 10, or against the gasket of felt 38 secured to the bottom of the panel 10 contiguous to its peripheral edge. When the top reaches the fully raised position shown in Fig. 7, the leaf 11 may be readily withdrawn to the position in which it is shown in Fig. 8, wherein the inner edge 11a of the leaf is vertically aligned with the peripheral edge 10a of the panel 10. When the leaf has been thus positioned, the top-operating mechanism is operated to lower the table top. However, the portions 33 of the leaf-supporting bars 30 and 31, then bearing as shown in Fig. 8 upon the upper edge of the skirt 2, support the leaf and prevent its downward movement, and it is at this stage in the operation that means come into play, to permit the panel 10 to descend relatively to the leaf, until both the leaf and the panel extend in a common horizontal plane, as shown in Fig. 9, in which position of the parts the table is serviceable with the one or both of the leaves extended, as shown in Fig. 2. The means providing for such relative vertical movement between the panel 10 and the extended leaves 11 and 12 are afforded by a feature of construction in the bearing devices 25; that is, the openings that retain the roller pins 37, 37 in each support portion 25a consist in vertical slots 39. By virtue of these slots, the bearing devices 25 (and with them the panel 10) may be lowered from the position indicated in Fig. 8 to that indicated in Fig. 9. It will be understood that when the table top is raised the roller pins 37, 37 bear against the bottoms of the slots and carry the roller pins, bars 30, 31 and leaves 11 and 12 upward with the panel, but, when the leaves are extended and bear upon the edge of the skirt 2, the slots 39 permit the bearing devices 25 to move downward relatively to the roller pins 37, 37, so that the panel 10 may descend into the plane of the extended leaves 11 and 12. The structure described, though of simple design, provides for sturdiness and strength, yet facility and accuracy of operation of the adjustable parts of the table.

In order to return the table top to its normal position (Fig. 1), the top-actuating mechanism

is manipulated to raise the panel 10 and the bearing devices 25 from the position shown in Fig. 9 to that shown in Fig. 8, relieving the pressure of the bar portions 33 on the edge of the skirt 2 of the table frame, or preferably lifting such bar portions free from engagement with the edge of the skirt. Thereupon, the leaves may be slid inward to retracted position beneath the panel 10 (cf. Fig. 7), and the entire top structure of the table then lowered to nested position within the upper edge of the skirt 2, in which position the leaves and all actuating mechanism are absolutely screened from view and from accumulations of dust and dirt.

As exemplary of the many variations in details of construction that may be utilized without departing from the spirit of my invention, I show in Fig. 10 a modification in the mechanism for raising and lowering the table top. Instead of journaling the shaft 24 in the vertically moving members 17 of the telescopic top-supporting devices, the shaft may be journaled at each end in the stationary outer members 15 at each end of the table. On each member 17 a cam roller 40 is mounted, to ride the edge of a disk cam 41 fixed on the shaft adjacent each telescopic supporting device 15, 17, and to one of the cams 41 a radial arm 42 is welded. The arm may be equipped with a handle (not shown) in the same way that the lever 26 is equipped, and thus the arm may be swung to rotate the shaft and the two cams thereon. When the shaft is rotated counterclockwise, as viewed in Fig. 10, the cam edges bearing upward against the rollers 40 effect the rise of the support member 17 and the table top, and, alternately, when the shaft is rotated clockwise, the table top is lowered. The bodies of the support members 17 of the two supporting devices include vertical slots 44, whereby interference of the shaft 24 with the desired vertical movement of the members 17 is avoided. Conveniently, a notch 43 is formed in the edge of each cam, adjacent to the point of maximum throw, so that when the table top is raised by the rotating cams into fully elevation position, the rollers 40 will enter the notches 43 and temporarily retain the top in elevated position, that is, until the leaves are drawn into extended position, whereupon the cams may be rotated to disengage the notches from the rollers and lower the table top or the panel 10 thereof.

I claim:

1. A table having a frame supporting a table top, said frame comprising a main panel and a leaf normally positioned beneath the panel, supporting bars for said leaf, a plurality of spaced bearing means secured to the under side of said panel engaging said supporting bars for horizontal and vertical movement of the supporting bars relatively to said panel, and means including a shaft extending between and journaled in said bearing means for vertically shifting said panel and bearing means, whereby the leaf may be drawn horizontally from beneath the panel and the panel positioned in the plane thereof.

2. A table having a frame provided with a skirt having a peripherally extending upper edge, a table top comprising a main panel and a leaf normally positioned beneath the panel and beneath said upper edge of the skirt, supporting means for said leaf, a plurality of spaced bearing means beneath the panel engaging said leaf-supporting means for horizontal and vertical movement of the supporting means relatively to the panel, and means including a shaft extend-

ing between and journaled in said bearing means for vertically shifting the panel and leaf to move the leaf into position above said upper edge of the skirt, whereby the leaf may be drawn horizontally from beneath the panel and the panel positioned in the plane thereof.

3. A table having a frame provided with a skirt having a peripherally extending upper edge, a table top comprising a main panel and a leaf normally positioned beneath the panel and beneath said upper edge of the skirt, supporting means for said leaf, a plurality of spaced bearing means secured to the bottom of the panel engaging said leaf-supporting means for horizontal and vertical movement of the supporting means relatively to the panel, and mechanism including a crank mounted on said frame and a shaft extending between and journaled in said bearing means for vertically shifting the panel and leaf to move the leaf into position above the upper edge of the skirt, whereby the leaf may be drawn horizontally from beneath the panel and positioned in the plane thereof.

4. A table having a frame supporting a table top, said table top comprising a main panel and a leaf normally positioned beneath the panel, means including at least one slide bar for supporting said leaf, said slide bar including a longitudinal slot, a bearing secured to the under side of said panel, a plurality of pins in said bearing extending through said slot at points spaced longitudinally thereof and engaging said slide bar to the bearing and providing for horizontal movement of the leaf relatively to said panel, said bearing including vertical slots providing for a vertical movement of said pins and the slide bar engaged thereby relatively to said panel, whereby said panel when said leaf is drawn horizontally from therebeneath may be positioned in the plane of the leaf, and means for vertically shifting said panel and bearing.

5. A table having a frame supporting a table top, said table top comprising a main panel and a leaf normally positioned beneath the panel, means including at least one slide bar for supporting said leaf, said slide bar including a longitudinal slot, a bearing secured to the under side of said panel, a plurality of pins in said bearing extending through said slot at points spaced longitudinally thereof and engaging said slide bar to the bearing and providing for horizontal movement of the leaf relatively to said panel, said bearing including vertical slots providing for a vertical movement of said pins and the slide bar engaged thereby relatively to said panel, whereby said panel when said leaf is drawn horizontally from therebeneath may be positioned in the plane of the leaf, and mechanism including a crank accessible beneath said panel for vertically shifting said panel and bearing into position to permit horizontal and vertical movements of said leaf relatively to the panel.

6. A table having a frame provided with a skirt having a peripherally extending upper edge, a table top comprising a main panel and a leaf normally positioned beneath the panel and beneath said upper edge of the skirt, means including at least one slide bar for supporting said leaf, said slide bar including a longitudinal slot, a bearing secured to the under side of said panel, a plurality of pins in said bearing extending through said slot at points spaced longitudinally thereof and engaging said slide bar to the bearing and providing for horizontal movement of the leaf relatively to said panel, means in the

assembled slide bar and bearing providing for the vertical movement of the bearing relatively to the slide bar whereby said panel when said leaf is drawn horizontally from therebeneath may be positioned in the plane thereof, and means for vertically shifting said panel, bearing and leaf into a position wherein the leaf lies above said upper edge of the skirt for horizontal movement outwardly thereof.

10. 7. A table having a frame supporting a table top, said table top comprising a main panel and a leaf normally positioned beneath the panel, a plurality of slide bars for supporting said leaf, a bearing for each slide bar secured to the bottom of the panel, means in said bearings and slide bars for engaging the respective slide bars to said bearings while providing for longitudinal movement of the engaged bars, whereby said leaf may be extended horizontally from beneath said panel, means in the assembled slide bars and bearings providing for the vertical movement of the bearings relatively to the bars and of the panel into the plane of the extended leaf, and means for vertically shifting said panel and bearings.

30. 8. A table having a frame supporting a table top, said table top comprising a main panel and a leaf normally positioned beneath the panel, a plurality of slide bars for supporting said leaf, a bearing for each slide bar secured to the bottom of the panel, a longitudinal slot in each slide bar, a plurality of pins in each bearing extending through the slot in the associate slide bar at points spaced longitudinally thereof and providing for horizontal extension of the leaf from beneath the panel, each bearing including vertical slots providing for vertical movement of the bearings relatively to the pins and the slide bar engaged thereby, whereby said panel when said leaf is drawn horizontally into extended position may be vertically shifted relatively to said leaf and into the plane thereof, and means for vertically shifting said panel and bearings.

45. 9. A table having a frame provided with a skirt having a peripherally extending upper edge, a table top comprising a main panel and a leaf normally positioned beneath the panel and beneath said upper edge of the skirt, a plurality of slide bars for supporting said leaf, a bearing for each slide bar secured to the bottom of the panel, means in said bearings and slide bars for engaging the respective slide bars to said bearings while providing for longitudinal movement of the engaged bars, whereby said leaf may be extended horizontally from beneath said panel, means in the assembled slide bars and bearings providing for the vertical movement of the bearings relatively to the bars and of the panel into the plane of the extended leaf, and means for vertically shifting said panel, bearing and leaf into a position wherein the leaf lies above said upper edge of the skirt for horizontal movement outwardly thereof.

60. 10. A table having a frame provided with a skirt having a peripherally extending upper edge, a table top comprising a main panel and a leaf normally positioned beneath the panel and beneath said upper edge of the skirt, a plurality of slide bars for supporting said leaf, a bearing for each slide bar secured to the bottom of the panel, means in said bearings and slide bars for engaging the respective slide bars to said bearings while providing for longitudinal movement of the engaged bars, whereby said leaf may be extended horizontally from beneath said panel,

means in the assembled slide bars and bearings providing for the vertical movement of the bearings relatively to the bars and of the panel into the plane of the extended leaf, and means for vertically shifting said panel, bearing and leaf into a position wherein the leaf lies above said upper edge of the skirt for horizontal movement outwardly thereof, said last means being operable to lower the panel into the plane of the leaf in extended position.

11. A table having a frame provided with a skirt having a peripherally extending upper edge, a table top comprising a main panel and a leaf normally positioned beneath the panel and beneath said upper edge of the skirt, a plurality of 15 slide bars for supporting said leaf, a bearing for each slide bar secured to the bottom of the panel, means in said bearings and slide bars for engaging the respective slide bars to said bearings while providing for longitudinal movement of 20 the engaged bars, whereby said leaf may be extended horizontally from beneath said panel, means in the assembled slide bars and bearings

providing for the vertical movement of the bearings relatively to the bars and of the panel into the plane of the extended leaf, and means for vertically shifting said panel, bearing and leaf into a position wherein the leaf lies above said upper edge of the skirt for horizontal movement outwardly thereof, said last means comprising an operating crank accessible beneath the table top for manipulation.
